(57) **CLAIM**

The ornamental design for a vaporizer heating assembly, as shown and described.

DESCRIPTION

FIG. 1 is a perspective downward-looking top view of a vaporizer heating assembly according to the present invention;

FIG. 2 is a perspective bottom view thereof;

FIG. 3 is top plan view thereof;

FIG. 4 is bottom plan view thereof;

FIG. 5 is a front elevation view thereof;

FIG. 6 is a rear elevation view thereof; and,

FIG. 7 is a side elevation view thereof.

The broken lines showing functional display characters on the top surface form no part of the claimed design.

The broken lines showing an interior of the outer box through the air output port on the front surface and the air-intake holes and a power input on the rear surface form no part of the claimed design.
